UNITED STATES PATENT OFFICE.

JAMES F. WARNER, OF ESSEX, VERMONT.

DESIGN FOR A SAP-SPOUT.

SPECIFICATION forming part of Design No. 31,860, dated November 21, 1899.

Application filed October 21, 1899. Serial No. 734,411. Term of patent 7 years.

To all whom it may concern:

Be it known that I, JAMES F. WARNER, a citizen of the United States, residing at Essex, in the county of Chittenden and State of Vermont, have invented a certain new and useful Design for Sap-Spouts; and I do hereby declare the following to be a full, clear, and exact description of the invention, such as will enable others skilled in the art to which it applies to make and use the same.

My invention relates to a design for sap-spouts, as illustrated in the accompanying drawings, in which—

Figure 1 is a top perspective view. Fig. 2 is an inverted perspective view. Fig. 3 is an enlarged cross-sectional view on the line 3 3 of Fig. 1. Fig. 4 is a cross-sectional view on line 4 4 of Fig. 1. Fig. 5 is a cross-sectional view on line 5 5 of Fig. 1.

My design consists of a body portion *a*, provided with a slot or trough portion *b*, an upwardly-extending projection *c*, and a downwardly-extending projection *d* at the outer

end of the slot *b*. The opposite end of the body portion *a* is provided with a short tapering portion *e* and an elongated tapered portion *f*, forming the opposite end of the body portion *a*. The inner end *f* is provided with the projecting beads or fins *g*, and the under side of the portion *f* is provided with an inwardly-extending opening *i*. Extending through the portions *f*, *e*, and *a* is a longitudinal opening *h*, communicating with the groove or trough *b*.

Having thus described my invention, what I claim, and desire to secure by Letters Patent, is—

The design for a sap-spout substantially as herein shown and described.

In testimony whereof I do affix my signature in presence of two witnesses.

JAMES F. WARNER.

Witnesses:

CHARLES E. ALLEN,
GILBERT A. DOW.
